DOOR CONTROL MECHANISM

Raymond U. Schneider, Chicago, Ill., assignor to
The Guardite Corporation, a corporation of
Illinois

Application May 31, 1940, Serial No. 338,210

8 Claims. (Cl. 268—58)

This invention relates to a door control mechanism and more particularly to automatic means of raising and lowering a vertical lift door in connection with a vacuum chamber.

The invention is illustrated in the drawings in which Fig. 1 is a front elevation of the door; Fig. 2 is a side elevation thereof; Fig. 3 is a sectional view taken along the line 3—3 in Fig. 1; Fig. 4 is a diagrammatic view of the valve control mechanism with the door lowered and in closed position; Fig. 5 is a similar view with the door lowered but in open position; Fig. 6 is a similar view with the door raised and open; and Fig. 7 is a similar view with the door raised but about to be lowered by its own weight.

The door is designed primarily for square or rectangular vacuum tanks such as those employed for treating tobacco. The end of such a tank 10 is indicated in Fig. 2. The rectangular opening provided in the end of the chamber is closed by the door 11 which is of steel plate reinforced by suitable cross members 12 and preferably provided with portholes 13 for inspection of the operation of the tank. The door is suspended by three cables 14, 15 and 16. Cable 15 is attached to a bracket 17 at the top of the door and extends over the sheave 18 and passes down under the pulley 19 up over the sheave 20 and is secured to the adjustable member 21 which is anchored to the supporting frame 22. The pulley 19 carries a shaft 23 which is connected to the piston 24 of the air cylinder 25. Air is supplied to the upper part of the cylinder through the opening 26 in the customary manner.

Cables 14 and 16 are attached to brackets 27 and 28, respectively, on the door 11, and are passed upwardly over sheaves 29 and 30 and are secured to a counterweight 31 of somewhat less weight than the door. The sides of the door are provided with blocks 32 in which are secured shafts 33 carrying rollers 34 which revolve about a horizontal axis parallel with the face of the door. The rollers 34 are guided by guide rail 35 which is pivotally mounted at 36, and an extension 37 of which extends beyond the top of the tank.

Upon each guide rail are brackets 38 which are connected in any suitable fashion, as by an arm 39, to the piston 40 of an air cylinder 41 to which air may be supplied under compression to the opening 42.

In operating the door, as for example, starting with the door originally in raised position, air is vented from the air cylinder 25 which permits the door to fall of its own weight, it being heavier

than the counterweight 31. When the door has dropped into position, air is passed into the air cylinder 41 with the result that the guide rail 35 is drawn toward the tank. This pulls the rollers 34 toward the tank and by this means the door itself is drawn into close contact with the tank. In raising the door the process is repeated, air being forced into the opposite side of the air cylinder 41 through the opening 43 and thus forcing the door away from the tank. Air is then admitted to the air cylinder 25 which lifts the door to its top position.

In Figures 4 to 7, inclusive, a valving arrangement is shown which permits this operation to be carried on with a minimum of manual control. In Figure 4 the door is closed. In the control system there is a needle valve 50 which is connected through a T 58 with a check valve 51 and a four-way valve 52. The manually controlled four-way master valve 52 is provided with an exhaust opening 53, an air supply opening 54, an opening 55 leading to air cylinder 25, and a fourth opening 56 leading to opening 59 of the automatic four-way valve 57. The other connections in this valve are an exhaust opening 60, an opening 61 leading to a second needle valve 62 which is connected through a poppet valve 63 with the air cylinder 41; and an opening 64 which is connected through the line 65 of the opposite side of the air cylinder 41.

The needle valve 50 is connected by the line 66 with the top of the air cylinder 25. The T 58 leads through the needle valve 50 to the air cylinder 25 and through the check valve 51 and the line 67 to the air cylinder 41.

When the door is lowered and shut, the master valve 52 is in its A position as shown in Figure 4 so that the openings 53 and 55 are connected and openings 54 and 56 are connected. This leads the air from opening 54 through 56 to opening 59 of the four-way valve 57. At the same time valve 57 is in its A position so that the opening 59 is connected to the opening 64, and opening 61 connects with 60. As a result, air passes from 59 to 64 and through the line 65 to the outside air cylinder 41. This forces the door into closed position. In order to raise the door, the valve 52 is turned from the A position to the B position. In the B position, as shown in Figure 5, openings 54 and 55 are connected so that the air supply is conducted to the T 58 and thence flows in two directions through the needle valve 50 and the check valve 51.

The capacity of the needle valve being quite small, the first result is for the air to rush

through the check valve 51 into the air cylinder 41 and push the door outwardly, the air from the opposite side of the piston being forced out through line 65 and openings 64, 59, 56 and 53.

The poppet valve 63 automatically closes as soon as the door starts up so that no leakage occurs through this line. However, before the door has started up, there is a negligible leakage of air through the poppet valve 63, the needle valve 62, and the exhaust opening 60.

When the door rises, a spring pressed treadle, which is held down by the weight of the door, opens, thereby permitting the poppet valve 63 to close and also moving the four-way valve 57 to position B. In this position, the line 65 exhausts through opening 60, whereas the other relationships are operatively unchanged except that the poppet valve 63 is now closed. The valves remain in this position so long as the door is up; but when it is desired to lower the door the four-way valve 52 is returned to the A position which connects the air cylinder 25 with the exhaust opening 53, permitting the air to exhaust slowly through the needle valve 50. The door control air cylinder 41, however, cannot exhaust through the check valve 51. However, when the door reaches the foot treadle, the four-way valve 57 is returned to the A position, as shown in Figure 4, and air may then exhaust from the left hand side of the cylinder through the poppet valve 63 which is then open, the needle valve 62, opening 61, and exhaust opening 60. At the same time the air supply is connected through openings 54, 56, 59, 64 and the line 65 to the right hand side of the cylinder so that the door is forced inwardly.

The arrangement of valves just described automatically raises or lowers the door and moves it into closed or open position merely by moving one valve. This makes it impossible to move the door inwardly while in raised position or to put the connections into an arrangement where the air will move in the wrong direction at the wrong time. The arrangement also moves the door into closed position slowly but moves it into open position rapidly.

The manner in which the valves 57 and 63 are operated by the door is shown in Figs. 4-7, inclusive. In Fig. 4 the door is down and in. In Fig. 5 it is down and out. In Fig. 6 it is up and out. In Fig. 7 it is moving downwardly and is still out. The valve 57 is provided with an operating arm 57a connected by a link 57b to the lever 80 pivoted at 81 and provided with a treadle 82 adapted to be engaged by the door 11 in its lowermost position. 83 indicates a spring normally tending to raise the treadle 82. When the treadle is down, the valve 57 is moved to the A position as shown in Figs. 4 and 5. When the door is up the spring 83 raises the treadle 82 and lowers the lever 80 to move the valve 57 to the B position as shown in Figs. 6 and 7. The lever 80 is also provided with a projection 80a adapted to engage the roller 84 on the valve rod 85 controlling the poppet valve 63 when the lever 80 rises. That is, when the door 11 depresses the treadle 82 and raises the lever 80, the poppet valve 63 is opened as shown in Figs. 4 and 5. When the door rises to release the treadle, the spring 86 on the poppet valve closes the same as shown in Figs. 6 and 7.

87 indicates a check valve in the pipe leading from the automatic valve 57 to the pipe 67. Air is free to pass through the check valves 51 and 87 in the direction indicated by the arrows but not in the reverse direction. The needle valve

50 has a restricted orifice 50a and the needle valve 62 has a restricted orifice 62a.

As described above, the door 11 is vertically movable to open or closed position. It is operated by the pneumatic device 25. For convenience, I shall refer to the raising and lowering of the door as opening and closing it. The small cylinders 41 move the door horizontally inwardly and outwardly. For convenience, I shall refer to this movement as sealing or unsealing the door. That is, when it is moved inwardly it is sealed. When it is moved outwardly it is unsealed.

The valve 52 is manually controlled. It has two positions—A, the door lowering or closing position, and B, the door opening or raising position. That is, the valve 52 can be operated manually to open or close the door. As shown in Fig. 4, the valve 52 is in door closing position and the door is closed and sealed (moved horizontally inwardly by the cylinders 41). When the valve 52 is moved to the B position, the door is first unsealed and then raised or opened. If the valve B then be moved to A position the door is closed and then sealed.

The foregoing detailed description has been given for clearness of understanding only, and no unnecessary limitations should be understood therefrom.

What I claim as new, and desire to secure by Letters Patent, is:

1. In combination with a door adapted to be moved vertically between open and closed positions, and horizontally between sealed and unsealed positions, control means, including: a pneumatic device adapted to open or close the door; a pneumatic device adapted to seal or unseal the door; a manually controlled valve for actuating said door opening and closing device, said valve when in door opening position adapted to actuate the door sealing device to move the door to unsealed position; and an automatic valve for operating said door sealing and unsealing device, said automatic valve adapted to be moved to door sealing position by the door when in its lowermost position.

2. In combination with a door adapted to be moved vertically between open and closed positions, and horizontally between sealed and unsealed positions, said door having sufficient weight normally to close by gravity, control means, including: a door opening cylinder; a door sealing and unsealing cylinder; a source of air pressure; and a manually controlled valve adapted to be moved to door opening position to admit air to both cylinders simultaneously, whereby said door will be unsealed and opened, or moved to door closing position, whereby the door opening cylinder will be vented permitting the door to close by gravity.

3. In combination with a door adapted to be moved vertically between open and closed positions, and horizontally between sealed and unsealed positions, said door having sufficient weight normally to close by gravity, control means, including: a door opening cylinder; a door sealing and unsealing cylinder; a source of air pressure; a manually controlled valve adapted to be moved to door opening position to admit air to both cylinders simultaneously, whereby said door will be unsealed and opened, or moved to door closing position, whereby the door opening cylinder will be vented permitting the door to close by gravity; and an automatic valve adapted to be operated by the door when in

closed position to admit air under pressure to the sealing cylinder to seal the door.

4. In combination with a door adapted to be moved vertically between open and closed positions, and horizontally between sealed and unsealed positions, said door having sufficient weight normally to close by gravity, control means, including: a door opening cylinder; a door sealing and unsealing cylinder; a source of air pressure; a manually controlled valve adapted to be moved to door opening position to admit air to both cylinders simultaneously, whereby said door will be unsealed and opened, or moved to door closing position, whereby the door opening cylinder will be vented permitting the door to close by gravity; an automatic valve adapted to be operated by the door when in closed position to admit air under pressure to the sealing cylinder to seal the door; and an automatic vent valve for the sealing cylinder adapted to be opened by the door when in its closed position.

5. In combination with a door adapted to be moved vertically between open and closed positions, and horizontally between sealed and unsealed positions, said door having sufficient weight normally to close by gravity, control means, including: a door opening cylinder; a door sealing and unsealing cylinder; a source of air pressure; a manually operated valve adapted to be moved to door opening position to admit air to both cylinders simultaneously, whereby said door will be unsealed and opened, or moved to door closing position, whereby the door opening cylinder will be vented permitting the door to close by gravity; and an automatic mechanism operated by the door when in its closed position to admit air under pressure to the door sealing and unsealing cylinder to seal the door.

6. In combination with a door adapted to be moved vertically between open and closed positions, and horizontally between sealed and unsealed positions, said door having sufficient weight normally to close by gravity, control means, including: a pneumatic door opening cylinder; a pneumatic door sealing and unsealing cylinder; a source of air pressure; a manually operable valve adapted to be moved between door opening and door closing positions; and an automatic valve normally in B position and adapted to be moved to A position by the door when the latter is in closed position; said manually operable valve when in door opening position adapted to admit air under pressure to both cylinders to unseal and open the door, said valve in said position operating in conjunction with the automatic valve in A position to vent the sealing cylinder to permit the unsealing operation thereof; said manually controlled valve when in door closing position operating in conjunction with said automatic valve in A position to admit air under pressure to the door sealing device to seal the door.

7. In combination with a door adapted to be

5 moved vertically between open and closed positions, and horizontally between sealed and unsealed positions, said door having sufficient weight normally to close by gravity, control means, including: a pneumatic door opening cylinder; a pneumatic door sealing and unsealing cylinder; a source of air pressure; a manually operable valve adapted to be moved between door opening and door closing positions; an automatic valve normally in B position and adapted to be moved to A position by the door when the latter is in closed position; said manually operable valve when in door opening position adapted to admit air under pressure to both cylinders to unseal and open the door, said valve in said position operating in conjunction with the automatic valve in A position to vent the sealing cylinder to permit the unsealing operation thereof; said manually controlled valve when in door closing position operating in conjunction with said automatic valve in A position to admit air under pressure to the door sealing device to seal the door; and a vent valve for the door sealing cylinder adapted to be operated by the door when in closed position to vent the door sealing cylinder to permit sealing of the door.

8. In combination with a door adapted to be moved vertically between open and closed positions, and horizontally between sealed and unsealed positions, said door having sufficient weight normally to close by gravity, control means, including: a door opening pneumatic cylinder; a door sealing and unsealing pneumatic cylinder with a piston therein connected to the door; a source of air pressure; a manually operable four-way valve connected to the source of air pressure and adapted to be moved between door opening and door closing positions; an automatic four-way valve normally in B position having mechanism adapted to be actuated by the door when in closed position to move said valve to A position; an automatic vent valve connected to the door sealing cylinder to permit movement of the piston therein to seal the door, said vent valve being normally closed, said valve having mechanism adapted to be actuated by the door when in closed position to open said valve; and suitable connections whereby said 30 manually operable valve when in door opening position connects said air pressure to the door sealing cylinder and the door opening cylinder to unseal and open the door and vents the door sealing cylinder through the automatic valve 35 in A position to vent the door sealing cylinder to permit unsealing of the door, and said manually operable valve when in door closing position vents the door opening cylinder permitting the door to close by gravity and connects the air 40 pressure through the automatic valve in B position to the door sealing cylinder to unseal the door and through the automatic valve in A position to the sealing cylinder to seal the door.

RAYMOND U. SCHNEIDER.
